UNITED STATES PATENT OFFICE.

JOSEPH H. POPE, OF HAMILTON, MASSACHUSETTS, ASSIGNOR TO UNITED SHOE MACHINERY COMPANY, OF PATERSON, NEW JERSEY, A CORPORATION OF NEW JERSEY.

MACHINE FOR STACKING HEEL-BLANKS.

1,088,720.

Specification of Letters Patent.

Patented Mar. 3, 1914.

Application filed December 12, 1906. Serial No. 347,540.

To all whom it may concern:

Be it known that I, JOSEPH H. POPE, a citizen of the United States, residing at Hamilton, in the county of Essex and Commonwealth of Massachusetts, have invented 5 certain Improvements in Machines for Stacking Heel-Blanks, of which the following description, in connection with the accompanying drawings, is a specification, like 10 reference characters on the drawings indicating like parts in the several figures.

This invention relates to machines for stacking heel blanks to facilitate handling such blanks in the manufacture of boots and 15 shoes, or in the course of the production of such blanks as separate articles of manufacture.

The invention will be herein described 20 with reference to the handling of top lifts, but it will be understood that substantially all of its features are capable of embodiment 25 in machines for arranging other heel blanks in a symmetrical order, for example heels instead of top lifts.

25 Top lifts prior to their attachment to heels are now commonly compressed to give them certain improved characteristics, the lifts being successively acted upon by a machine capable of producing the degree of 30 compression required. After being compressed, it is desirable to sort or grade them according to the quality of the stock, there being considerable variation in the quality 35 of the lifts before compression and some lack of uniformity existing after compression. The most important criterion of 40 quality is the appearance of the grain side, the presence of wrinkles, for example, upon this side detracting from the quality of the 45 finish which may be given it in the finishing operation. The compressed lifts are sorted by workmen who note the quality of each lift and assign it to its appropriate grade. Heretofore, in grading lifts, they have been 50 supplied in disorder to the workmen for the grading operation. In grading the lifts the workmen find it desirable to first arrange them in line, flesh side to grain side, and then deal the successive lifts into their appropriate places, this course permitting them to be rapidly sorted. A skilled workman can in this way sort them with great

rapidity as he is usually able by glancing at the grain side of a lift to detect its quality.

The present invention contemplates the 55 provision of mechanism for arranging top lifts in order, flesh side to grain side, so as to render unnecessary a preliminary arrangement of the lifts by hand prior to sorting them. To this end, in the present embodiment of the invention, I provide a receiver which is arranged to permit lifts from a compressing machine to be fed into it successively, and is constructed to sustain a number of lifts in a parallel relation 60 face to face. Means are provided for transferring into position in said receiver successive lifts from the dies of the compressing machine, which in the compressing machine shown are discharged laterally, curved 65 end foremost from operative relation to said dies. The lifts compressed in this machine have a uniform position in the die cavity, and the transferring means may therefore be arranged to act uniformly upon the lifts 70 and subject them to one and the same treatment, in order that when positioned in the receiver they will face in the same direction and have their respective edge faces in alignment. The receiver may conveniently 75 be formed as a horizontal trough constructed to support a row of lifts on end face to face, and is preferably arranged to support them breast end uppermost. The lifts when discharged from the compressor herein referred to lie upon one side, and I have accordingly arranged in their path mechanism 80 for raising them on end and arranging them in the receiver in an upright position. The lifts may conveniently be 85 introduced into the receiver at one end, the contents of the receiver being moved along automatically at the introduction of each lift. A convenient construction for positioning the lifts in the receiver comprises a carrier arranged at the entrance to the receiver and constructed to be moved from an approximately horizontal 90 position, in which it receives a lift into a vertical position. In its movement into vertical position the carrier raises the lift and places it on end within the receiver, the arrangement being such that the return of the lift with the carrier as the carrier moves 95 100

into its original position, is prevented. To facilitate removal of the blanks from the machine the receiver herein illustrated is formed in a plurality of sections. The section farthest removed from the point of introduction of the blanks, and which is hereinafter termed an auxiliary receiver, is arranged for detachment from the machine and accordingly constitutes a convenient means for transferring the blanks from the machine to the point of use.

Other features of the invention will be hereinafter described and defined in the claims.

15 In the drawings:—Figure 1 is a view in perspective of the more important parts of a machine embodying my invention. Fig. 2 is a view in perspective of a device which may be employed to store the lifts. Fig. 3 is a view in side elevation with parts in section of a portion of the machine. Fig. 4 is a view in perspective of a portion looking from below in Fig. 1. Fig. 5 is a view in perspective of a detail.

25 In the embodiment of the invention herein described, the blanks to be arranged in order are top lifts received from a compressing machine of the construction shown in United States Letters Patent No. 776,787, dated December 6, 1904. In this compressor a head 1 is raised and lowered once in each cycle of operations, and an ejector 2 is advanced into the position shown in Figs. 1 and 3 at approximately the end of the downward movement of the head 1 to push the compressed top lift from the top lift plate curved end foremost and flesh side uppermost. Heretofore, the lifts when discharged from the compressor have entered a chute 4 leading to a convenient receptacle.

In embodying my invention in a machine for arranging top lifts discharged for a compressor of the construction shown in said Letters Patent, the compressor is preferably not materially changed. Certain parts of this compressor above referred to, in themselves without novelty, coöperate with certain novel elements and devices shown herein to arrange the top lifts in the manner desired. It will be understood with reference to the present description that the compressor and in particular the ejecting mechanism thereof, while without novelty *per se*, constitutes an element of novel combinations hereinafter described, and in the present embodiment of the invention contributes to securing a uniform arrangement of the top lifts in the receiver.

In the present embodiment of the invention a bracket 4 is secured to the rear face of the compressor frame and is provided with a horizontal bore at its upper end to receive a rod 6, held in said bore by a set screw 8. Arranged adjacent to each end upon the rod 6 are hubs 10, 12, rigidly secured to the rod,

as by set screws 14. The sleeves 10, 12 are provided with upward extensions to which the plate 16 forming the bottom of the receiver is secured. The plate 16 may conveniently be of wood, and its upper face is concave in transverse section, to receive upon it the curved ends of the lifts. The sides of the receiver are formed of thin metal plates 18, 20 and arms 22, 23, 24 and 25 secured to said plates respectively to sustain them in position, said arms being supported by the rod 6. As shown the lower ends of the arms 22, 24 are formed as collars 26, 28 rotatably sustained by the shaft 6 and the lower ends of the arms 23 and 25 are similarly provided with collars 27, 29 bearing upon said shaft. Segmental bevel gears 32, 30 are formed on the bottom of the collars 26, 28, respectively, with their teeth facing, and a bevel gear 34 is arranged between and in engagement with said segmental gears, said gear being pivoted on the hub 10. The collars 27 and 29 are provided with similar opposed segmental gears 31, 33 in mesh with a bevel gear 35 sustained upon the hub 12. Springs 36, 37 are connected to said arms 22 and 24, and 23 and 25 tending to hold the sides of the receiver inwardly. It will be seen that the gear connections between the arms 22 and 24, and 23 and 25 insure that the two arms of each pair will move equally in opposite directions, and hence a symmetrical arrangement of the sides 18, 20 with relation to the center of the receiver is insured. As shown, the gear 34 is provided with an operating handle 370 and the hub 10 is provided with perforations 38 arranged at intervals and adapted to receive a removable pin 40, projecting into the path of the handle 370. It will be seen from the drawings that the spring 36 holds the handle 370 against the pin 40, so that the position of the pin 40 in the series of perforations 38 determines the position of the sides 18 and 20 and hence the width of the receiver.

A carrier 42 is secured to a horizontal shaft 44 pivotally sustained by the bracket 4 at the entrance to the receiver. A coiled spring 46 secured to the shaft 44 at one end and to the bracket 4 at the other holds the carrier 42 yielding in its lower position, shown in Fig. 3. A quadrant 48 is fixed upon the shaft 44 at one end and is provided with a grooved edge to receive a chain 50, which is secured at one end to the rear end of the quadrant 48 and at its other end to the head 1 of the compressor. It will be seen that in the upward movement of the head the carrier 42 is raised into a vertical position by the chain 50, the carrier resting against and traveling with the head through a part of its path of movement, and that as the head descends the spring 46 returns the carrier to its lower position. It will be

noted by an inspection of Fig. 3 that the path of vertical reciprocation of the head intersects the arc-shaped path through which the carrier 42 travels and that the 5 carrier will be pressed by the spring 46 against the head, and will receive motion from it until the head has risen far enough to take up the slack in the chain 50, shown in this figure. The carrier is thus maintained by the spring 46 in lift-receiving position with relation to the head during a portion of its movement in order to insure the reception by it of all lifts discharged by the ejector 2. In the raised position 10 of the carrier 42 said carrier is approximately flush with the end of the side walls 18, 20. The quadrant 48 is adjustably secured upon the shaft 44, as by means of a set screw 49, to permit the 15 raised position of the carrier 42 to be controlled accurately. The carrier is provided with ribs 52 which are secured thereto by set screws pivotal adjustment of said ribs 52 about the set screws being permitted. 20 The ribs 52 serve to position the top lift upon the carrier deflecting it into a central position, in case the ejector 2 does not advance the top lift centrally of said carrier. A stop 52' upon the carrier 42 limits rearward movement of the blank upon the carrier. Extending from the forward end of each of the sides 18, 20 are curved guides 25 54, extending forwardly and downwardly, and arranged to engage the sides of a blank 30 yieldingly in the upward movement of the carrier 42 and guide the blank into the end of the receiver. The carrier is provided with apertures 56 to receive the guides 54, and said guides are held together at their 35 lower ends by the device shown in Fig. 5 comprising a rod 58 having a series of notches 60 at one end and a head 62 at the other. The notches 60 engage an aperture in one of the extensions 54, said aperture 40 being enlarged at its upper end as shown to permit disengagement of the rod and relative adjustment of the guides 54 in the manner desired.

An upwardly projecting lug 64 is carried 50 by the bracket 4 and projects above the bottom of the receiver at its entrance. Flat springs 66 are arranged on the inner side of each of the guides 54. The springs 66 and lug 64 serve to prevent return of a 55 blank after its introduction to the receiver, the springs 66 yielding in the upward movement of the blank and the carrier 42 advancing the blank over the lug 64. The use of the springs 66 and lug 64 is not essential, 60 as the sides 18 and 20 may be adjusted relatively to engage frictionally the edges of the blank and hold it from return movement. The sides 18 and 20 and guides 54 are preferably so adjusted that the lower 65 ends of said guides are arranged slightly

farther apart than the upper ends so that the top lift will pass freely between the lower ends of said guides when said lift is advanced by the ejector 2. As the top lift is raised by the carrier 42 its edges are engaged by the guides 54 and the lift is thus guided into the open end of the receiver. 70

The receiver is preferably provided with a removable extension in which the blanks may be carried to the place desired. A convenient construction of auxiliary receiver is that shown comprising two sections 68, 70 formed of wood, and having their inner faces shaped to provide a trough approximately U-shaped. The sections 68, 70 may 75 be as long as may be conveniently handled and are connected by means permitting their adjustment to vary the width of the cavity formed between them. As shown, to each end of the sections 68 and 70 are secured plates 72 having bosses 73 provided with internally threaded bores arranged in line. A rod 74, having its ends oppositely threaded is arranged in said bores and is provided with a centrally arranged milled 80 disk 76. By turning the threaded rods 74 the sections 68, 70 may be adjusted to or from one another. The sections 68, 70 may 85 be connected to the main receiver by pins 78 upon the hub 12 entering slots 80 in said sections. The free end of the auxiliary receiver may be supported in any convenient 90 way.

In the operation of the machine shown a top lift upon being pushed from the top lift 100 plate of the compressing machine curved end foremost by the ejector 2 passes on to the carrier 42, which, as shown in Fig. 3, is then in an approximately horizontal position. The ribs 52 are engaged by the curved 105 end of the top lift so that it is deflected into central position in case the ejector 2 fails to advance it in the precise path desired. The movement of the top lift into position upon the carrier occurs at approximately 110 the end of the downward movement of the head 1. As the head 1 rises to compress another top lift the carrier is moved pivotally by the chain 50 into an upright position 115 at the entrance to the receiver. The curved guides 54 engage the sides of the top lift in its upward movement and guide it into the open end of the receiver. As the carrier reaches the end of its upward movement in which it is approximately flush with the end of the receiver the top lift is inserted in the open end of the receiver. In its movement into the open end of the receiver the top lift advances the contents of the receiver and passes by the springs 66. In the downward movement of the head 1 the carrier returns 120 to its initial receiving position, so that it is in position to receive another top lift at approximately the end of said downward movement. As the top lifts accumulate in 125 130

the receiver they are advanced into the auxiliary section. From time to time the auxiliary section may be disconnected from the main section and carried with its contents 5 to the sorting table. By inverting this auxiliary section the top lifts are conveniently deposited in a row on edge upon the table in position to be sorted, the lifts in the construction shown being so arranged that as 10 the auxiliary section is inverted they are deposited upon their breast edges. This insures their maintaining their register with each other in the row.

It will be seen that top lifts or heels which 15 have been stacked by the machine shown herein are in proper relation to be supplied conveniently to magazines, so that if it should be desired to employ magazines to store blanks, for example, in a heel attaching 20 or other machine, my invention would form a useful adjunct to such a machine in facilitating the supply of heel blanks to the magazines. Machines embodying the present invention may also be used to advantage 25 in arranging compressed heels or top lifts in convenient form for packing,—for example where they are produced as separate articles of manufacture.

Having described my invention, what I 30 claim as new and desire to secure by Letters Patent of the United States is:—

1. The combination with a machine for acting upon heel blanks successively, of a receiver constructed to sustain the blanks in 35 a parallel relation face to face, movable means for transferring said blanks from operative relation to said machine, into position in said receiver, and means for causing said blanks to be properly positioned upon 40 said transferring means.

2. The combination with a machine constructed to act upon heel shaped blanks successively and to discharge them rounded end foremost lying loosely upon one side, 45 of a receiver arranged to sustain the blanks on edge, and means in the path of the blanks from said machine for positioning the blanks on edge in the receiver, said means having provisions for causing the blanks to 50 register with each other as they enter the receiver.

3. The combination with a machine for acting upon heel shaped blanks successively constructed to discharge them by movement 55 in the direction of the length of the blanks, of a receiver constructed to sustain the blanks in parallel relation face to face, and means for transferring said blanks from said machine to said receiver, said means being arranged to receive blanks as they are 60 discharged from said machine and having provision for so positioning the blanks as to insure their proper register with each other when transferred to the receiver.

4. A support for heel blanks comprising 65 a normally horizontal trough open at the top and having its bottom transversely curved to conform approximately to the contour of the curved end of a heel, and arranged to support a series of blanks on edge 70 with their breast ends uppermost, said trough being reversible to deposit the series of blanks with their breast ends downward.

5. A support for heel blanks comprising 75 an open trough formed to support the blanks on their rounded edges face to face along its length, said trough being reversible to permit the blanks therein to be deposited upon their breast edges and being adjustable in width to accommodate blanks of 80 different widths.

6. A support for heel blanks comprising a concave base and plane sides arranged to support the blanks on end face to face and in register with each other, the sides of the 85 support being relatively adjustable to receive between them blanks of different widths to be similarly supported, said support being vertically open to permit removal of the blanks in the direction of their 90 length.

7. A support for heel blanks comprising a concave base and plane sides arranged to support the blanks on end face to face and in register with each other, the sides of the 95 support being relatively adjustable to receive between them blanks of different widths, and means for controlling the adjustment of the sides of the support arranged to maintain said sides in a symmetrical relation to the base of the support, said support being vertically open to permit removal of the blanks in the direction of their 100 length.

8. The combination of a movable head, a 105 mold upon said head, a feed slide, for supplying a blank to said mold, provided with means for removing a compressed blank from the mold, a carrier movable from a substantially horizontal blank 110 receiving position to a substantially vertical blank delivering position, said carrier being located and constructed to receive a compressed blank from said means and to keep the blank continually under control until 115 delivery; and a receiving device located to receive a blank delivered by said carrier.

9. The combination of a movable head, a 120 mold upon said head, means for ejecting a blank horizontally from said mold, a carrier pivoted to swing about a horizontal axis from a substantially horizontal blank receiving position to a substantially vertical blank delivering position, said carrier being located and constructed to receive a compressed blank from said means and to keep the blank continually under control until 125 delivery to a substantially vertical blank de-

livering position, and a receiving device arranged to receive a blank in vertical position from said carrier.

10. A support for heel blanks formed to sustain the blanks on edge face to face along its length and arranged for adjustment in width to accommodate blanks of different sizes, and means operating at separate points along the sides of the support for maintaining said sides in a parallel relation in their relative adjustment.

11. A machine for stacking heel blanks, having, in combination, a primary receiver constructed to sustain a series of blanks in a predetermined relation, means for supplying blanks successively to the primary receiver and for positioning them in said receiver, and an auxiliary detachable receiver arranged to form a continuation of said primary receiver and adapted to constitute a receptacle for conveying the blanks in their preadjusted relation.

12. In a machine of the class described, the combination with a head arranged for vertical movement and a compressing mold carried by the head, of means for feeding blanks to the mold, a receiver for the blanks, means for transferring blanks from the movable head to the receiver including a carrier independent of the blank feeding means for receiving and presenting to the receiver the compressed blanks discharged from the mold, and means actuated by the movement of the head to actuate the carrier.

13. In a machine of the class described, the combination of a head arranged for vertical movement, a compressing mold carried by the head, and an ejector arranged to discharge from said head during its movement 40 a compressed heel blank in a plane substantially at right angles to the line of movement of the head, a stationary receiver for the compressed blanks, and a movable carrier for receiving and sustaining a blank discharged from the moving head by the ejector, said carrier being arranged to present said blank to the receiver during the vertical movement of the head.

14. The combination of a vertically movable head, a mold carried by said head, a carrier movable into substantially horizontal blank receiving position upon descent of the head, and into substantially vertical blank delivering position upon ascent of the head, and a blank receiving device arranged to remove the blank from said carrier when the latter is in said vertical blank delivering position.

15. The combination with a machine for 60 acting upon heel blanks successively, of a receiver constructed to sustain the blanks in parallel relation face to face, said receiver being provided with extensions of its sides extending beyond the base of the receiver, 65 means for guiding the blanks between said

extensions as they are discharged from the machine, and means for positioning the blanks on edge in said receiver.

16. The combination with a machine for acting upon heel blanks successively, of a 70 receiver constructed to sustain the blanks in parallel relation face to face, movable means for transferring said blanks from said machine to said receiver, said means being arranged to receive the blanks as they are discharged from said machine, and means for centering the blanks on the transferring means as they are discharged thereupon.

17. The combination with a machine for acting upon heel blanks successively, of a 80 receiver arranged to sustain the blanks on edge, movable means for transferring the blanks from the machine to the receiver, said means being arranged to receive the blanks as they are discharged from the machine, and means coöperating with the transferring means to bring the blanks into proper transverse relation to said receiver as they are discharged upon said transferring means.

18. The combination with a machine for acting upon heel blanks successively, of a receiver arranged to sustain the blanks on edge, movable means for transferring the blanks from the machine to the receiver, said 95 means being arranged to receive the blanks as they are discharged from the machine, means coöperating with the transferring means to bring the blanks into proper transverse relation to said receiver as they are 100 discharged upon said transferring means, and means for maintaining the blanks in such proper transverse relation while they are being transferred to said receiver.

19. The combination with a machine for 105 acting upon heel blanks successively, of a receiver arranged to sustain the blanks on edge, movable means for receiving the blanks as they are discharged from said machine and then transferring them to said 110 receiver, of means adjustable laterally to accommodate blanks of different widths for guiding the blanks into proper transverse relation to said receiver as they are discharged upon said transferring means and 115 for maintaining the blanks in proper relation upon said transferring means as they are transferred to the receiver.

20. The combination with a machine for 120 operating upon heel blanks successively in a horizontal position, of a receiver for sustaining the blanks on edge, movable means for transferring the blanks from the machine to the receiver constructed to move 125 said blanks from a horizontal position to a vertical position, and means for confining the blanks against movement laterally with respect to the path of transfer from the time they are discharged from said machine until they are delivered to said receiver. 130

21. The combination with a machine for acting upon heel blanks successively in a horizontal position, of a receiver arranged to sustain said blanks on edge and means for transferring said blanks from said machine to said receiver constructed to move said blanks from a horizontal position to a vertical position, lateral guides upon said transferring means and lateral guides along the path of transfer, said guides coöoperating to bring said blanks into proper transverse relation to said receiver. 40
22. The combination with a machine for acting upon heel blanks successively, of a receiver arranged to sustain said blanks on edge and means for transferring said blanks from said machine to said receiver, adjustable lateral guides upon said transferring means and adjustable lateral guides along the path of transfer, said guides coöoperating to bring said blanks into proper transverse relation to said receiver. 45
23. The combination with a machine for acting upon heel blanks successively, comprising a head arranged for vertical movement, of a stationary receiver for heel blanks, a carrier for transferring said blanks from said head into position in said receiver, means operating to hold said carrier normally in blank-receiving relation to said head, and means for moving said carrier away from said head to transfer the blanks to said receiver. 50
24. The combination with a machine for acting upon heel blanks successively comprising a head arranged for vertical movement, of a receiver for heel blanks, a carrier yieldingly maintained normally in con- 55
- tact with said head and traveling with said head during a portion of its vertical movement, and means for actuating said carrier to transfer the blanks from said head to said receiver. 60
25. In a machine of the class described, the combination with a head arranged for vertical movement and a compressing mold carried by the head, of a receiver for heel blanks, a carrier for presenting to the receiver the compressed blanks discharged from the mold, means actuated by the movement of the head to actuate the carrier and means for maintaining the carrier in contact with the head during a portion of its vertical movement. 65
26. In a machine of the class described, the combination with a head arranged for vertical reciprocation and a compressing mold carried by the head, of means for feeding blanks to the mold, a stationary receiver for the blanks, a carrier independent of the feeding means arranged to receive blanks discharged from said mold and present them to the receiver, and connections between said head and carrier for operating the carrier, the parts being so arranged that the carrier is moved to position for receiving a blank on the downward movement of the head. 70

In testimony whereof I have signed my name to this specification in the presence of two subscribing witnesses.

R. F. WHITEHEAD,

Acting Commissioner of Patents.

21. The combination with a machine for acting upon heel blanks successively in a horizontal position, of a receiver arranged to sustain said blanks on edge and means for transferring said blanks from said machine to said receiver constructed to move said blanks from a horizontal position to a vertical position, lateral guides upon said transferring means and lateral guides along the path of transfer, said guides coöoperating to bring said blanks into proper transverse relation to said receiver. 40
22. The combination with a machine for acting upon heel blanks successively, of a receiver arranged to sustain said blanks on edge and means for transferring said blanks from said machine to said receiver, adjustable lateral guides upon said transferring means and adjustable lateral guides along the path of transfer, said guides coöoperating to bring said blanks into proper transverse relation to said receiver. 45
23. The combination with a machine for acting upon heel blanks successively, comprising a head arranged for vertical movement, of a stationary receiver for heel blanks, a carrier for transferring said blanks from said head into position in said receiver, means operating to hold said carrier normally in blank-receiving relation to said head, and means for moving said carrier away from said head to transfer the blanks to said receiver. 50
24. The combination with a machine for acting upon heel blanks successively comprising a head arranged for vertical movement, of a receiver for heel blanks, a carrier yieldingly maintained normally in con- 55
- tact with said head and traveling with said head during a portion of its vertical movement, and means for actuating said carrier to transfer the blanks from said head to said receiver. 60
25. In a machine of the class described, the combination with a head arranged for vertical movement and a compressing mold carried by the head, of a receiver for heel blanks, a carrier for presenting to the receiver the compressed blanks discharged from the mold, means actuated by the movement of the head to actuate the carrier and means for maintaining the carrier in contact with the head during a portion of its vertical movement. 65
26. In a machine of the class described, the combination with a head arranged for vertical reciprocation and a compressing mold carried by the head, of means for feeding blanks to the mold, a stationary receiver for the blanks, a carrier independent of the feeding means arranged to receive blanks discharged from said mold and present them to the receiver, and connections between said head and carrier for operating the carrier, the parts being so arranged that the carrier is moved to position for receiving a blank on the downward movement of the head. 70
